UNITED STATES PATENT OFFICE.

LOUIS SANDERS, OF BROOKLYN, NEW YORK.

DESIGN FOR A HAND-BAG.

SPECIFICATION forming part of Design No. 27,775, dated October 26, 1897.

Application filed September 14, 1897. Serial No. 651,683. Term of patent 31 years.

To all whom it may concern:

Be it known that I, LOUIS SANDERS, a citizen of the United States, residing at Brooklyn, in the county of Kings and State of New York, have invented and produced a new and original Design for a Hand-Bag, of which the following is a specification, reference being had to the accompanying drawing, forming a part thereof, in which is represented a perspective view of a hand-bag embodying the features of my design.

The design relates to that class of bags which have one compartment above the other and in which the lower compartment is reached by breaking the bag between its ends.

The leading feature of the design consists in the formation of the bottom portion A, which simulates an opera-glass case, including the body and top, and the upper portion B, which appears attached to the casing-section and which is apparently of a collapsible nature. The lidded mouth C may be of any desired shape, and likewise the loop D, shown connected with the mouth portion of the bag. 25

I claim—

The design for a hand-bag herein shown and described.

LOUIS SANDERS.
